SIGNALING DEVICE

Carl R. Weinert, Pittsburgh, Pa., assignor, by
mesne assignments, to The Timken Roller
Bearing Company, Canton, Ohio, a corporation
of Ohio

Application December 29, 1934, Serial No. 759,699

8 Claims. (Cl. 116—106)

This invention relates generally to signaling devices adapted to operate at a predetermined temperature to protect a structure against excessive temperature.

5 Although the signaling device is adapted for use with structures in general which are to be protected against excessive temperature, it will be described herein more particularly as applied to a rolling mill, and more especially as applied 10 in such manner as to protect the bearings of a rolling mill from reaching excessive temperatures which would cause them to burn up.

Generally speaking, the signaling device is placed adjacent to the part to be protected, for 15 example in a recess in the bearing block of a rolling mill. The signaling device comprises a signaling charge which may be liquid, solid or gaseous. The signaling charge is placed in the recess in the bearing block in such position as to be operated upon by a striking head. In those 20 cases where a liquid signaling charge is employed, it may be placed in a frangible container such as glass. The striking head also is placed in the recess in such position that when it is released it breaks the frangible container, allowing 25 the liquid signaling material to run out of a drain opening in the bearing block. The signaling material may be of a type such that upon contact with air it produces a smoke which directs the 30 attention of the operator to the bearing. The striking head is retained by means which includes an easily fusible retaining member, such as a low-melting point metal or other suitable material. A firing spring is usually provided which 35 exerts force against the striking head. When the retaining member of easily fusible material attains its softening temperature, it is sheared, thereby releasing the striking head which acts upon the signaling charge to liberate smoke, produce 40 lachrymation or stench, or fire a blank cartridge, any of these devices being suitable for calling the attention of the operator to the part to be protected by the signaling device.

In the accompanying drawings, which illustrate 45 several embodiments of my invention and which are given merely for purposes of illustration without limiting the invention thereto,

Figure 1 is a somewhat diagrammatic side elevation of a rolling mill housing equipped with 50 roller bearings, the bearing blocks being provided with signaling devices in accordance with the present invention;

Figure 2 is a sectional view through a portion 55 of the bearing block and showing one of the signaling devices located in the block;

Figure 3 is a view similar to Figure 2, but illustrating a slightly modified form of signaling device;

Figures 4 through 8 are sectional views illustrating different types of retaining means for 5 the striking head. These retaining means may be employed with any of the structures shown in the other figures;

Figure 9 illustrates an arrangement in which there are two striking heads which are placed 10 within a frangible container containing a liquid signaling material;

Figure 10 is a sectional view through a portion 15 of a bearing block, the bearing block in this case being used for supporting a vertical roll instead of a horizontal roll, as in the other embodiments, the recess in the bearing block of Figure 10 extending in a vertical direction;

Figure 11 is a view similar to Figures 2 and 3, but containing a solid charge of signaling material adapted to liberate lachrymation or stench 20 gas upon ignition of the charge; and

Figure 12 is a view similar to Figures 2, 3 and 11, but containing a blank cartridge which when 25 acted upon by the striking head produces a noise.

Referring more particularly to the accompanying drawings, and for the present to Figure 1, there is shown somewhat diagrammatically a housing 2 of a rolling mill. The mill may be provided with the usual bearing blocks 3 for supporting roller bearings 4. The bearing blocks are provided with recesses 5 adjacent the roller bearings and signaling devices, indicated generally by the reference numeral 6 and adapted to operate when the bearings reach a predetermined temperature, are located in the recesses 5.

Referring to Figure 2, the signaling device comprises a striking head 7 retained in a retaining sleeve 8. The retaining sleeve is provided with an annular interior flange 9, against one side of which bears a firing spring 10, the other end of the spring pressing against the striking head 7. The threaded end 11 of a bolt 12 is threaded into the shank 13 of the striking head. The head 14 of the bolt presses against a washer 15 which seats against one side of the annular flange 9. The striking head 7 is accordingly retained in position against the action of the spring 10 by the washer 15. The washer may be made of an easily fusible metal such as "Woods" metal and consisting essentially of lead, tin, bismuth and cadmium. This particular metal softens at a temperature of about 174° F. Other easily fusible metals or alloys or other materials may be employed dependent upon the temperature at which 55

it is desired the retaining washer soften. Where it is desired that the retaining member or washer melt at very low temperatures, alloys of mercury may be employed or even non-metallic materials such as beeswax may be used.

5 A glass or other frangible container 16 containing a liquid signaling material is also placed in the recess 5. One substance suitable for this purpose is titanium tetrachloride which, upon 10 contact with moisture, forms titanium oxide and hydrochloric acid, thereby producing a smoke. Other liquid smoke producing materials, such as a mixture of chlorosulfonic acid and sulfur trioxide, may be employed, or as hereinafter de- 15 scribed, solid materials may be used.

The retaining sleeve 8 is maintained at one end of the recess in the housing by a spacing means such as a perforated metal cylinder 17. The open end of the recess in the housing is closed by 20 an end plug 18 which is threaded into the recess, and for this purpose is provided with holes 19 for receiving a spanner wrench. The end plug is also provided with an air vent 20 and the bearing block is provided with a drain opening 21.

25 The operation is as follows: When the bearing 4 reaches a predetermined temperature corresponding to the softening temperature of the washer 15, the spring 10 causes the head 14 of the bolt 12 to shear the washer and the striking 30 head 7 is thereby released. The striking head breaks the container 16 and allows the liquid signaling material to run out through the openings in the cylinder 17 and the drain hole 21, thereby producing a smoke which attracts the attention 35 of the operator.

In the embodiment shown in Figure 3, the construction is identical with that shown in Figure 2, except that a spring 25 is used in place of the perforated metal cylinder 17 for retaining the 40 retaining sleeve 8 in place and providing openings through which the liquid signaling material may run out while preventing the broken glass of the container from clogging the opening 21.

45 Various other means may be used in place of the washer 15 shown in Figure 2 for retaining the striking head 7 against the pressure of the spring 10. In Figure 4 the head 26 of the bolt 12 is made of easily fusible metal and the shank 50 27 of the bolt passes through an opening 28 formed in the sleeve 8. When the bolt head 26 reaches the predetermined temperature, it shears from the shank 27, thereby releasing the striking head 7 which acts upon the signaling charge 55 as previously described.

In the embodiment shown in Figure 5, a washer 29 of easily fusible material is used for retaining the striking head 7 against the tension of the spring 10. The washer 29 seats against a 60 shoulder 30 formed in the sleeve 8 and the spring is compressed between an annular flange 31 and the head 7.

Figure 6 illustrates a modification in which a cup-shaped retaining means 32 is employed. The 65 shank 33 of the striking head is threaded into an end 34 of the retaining means and a spring 35 surrounds the shank and presses against the striking head 36 and against the end 34 of the retaining means. A portion 37 of the shank of the 70 striking head is made of easily fusible metal so that when the device reaches the predetermined temperature, the shank parts, thereby releasing the striking head 36.

In the device shown in Figure 7, a striking head 75 40 extends partially through an opening in a

plate 41 of easily fusible metal, the head being under the compression of a spring 42 having one end bearing against a plate 43. The plates 41 and 43 are connected by bolts 44. Similarly to the other embodiments, the head 40 is released 5 when the plate 41 reaches its softening tempera- ture.

In the embodiment shown in Figure 8, one end 45 of a bolt is threaded into a striking head 46 and the other end 47 fits into a socket 48 carried 10 by a retaining member 49. The end 47 of the bolt and the socket 48 are formed with openings which receive a shear pin 50 of easily fusible metal which may be placed in position through openings 51 in the retaining member. A compression spring 52 is also provided for the striking head. The shear pin 50 shears when it reaches a predetermined temperature, thereby re- 15 leasing the striking head 46.

Instead of locating the striking head and retaining means outside of and spaced from the charge of signaling material, they may, when the signaling material is a liquid or gas, be placed within the frangible container containing the liquid or gaseous signaling material. Such an 20 arrangement is shown in Figure 9. A glass container 55 containing liquid signaling material 56 is closed by a glass plate 57 retained by a metal ring 58 which is threaded onto the container, the plate being sealed by a washer 59 of 30 rubber or other suitable material. Inside of the container are two striking heads 60, the shanks 61 and 62 being provided, respectively, with a recess 63 and a projection 64. A pin 65 of easily fusible metal connects the two shanks together 35 and retains them in position against the action of a compression spring 66. Upon the device reaching a predetermined temperature, the pin 65 is sheared and the striking heads 60 break 40 the container, liberating the charge 56. It will 45 be understood that the container is placed in a recess in the bearing or other structure which it is desired to protect against excessive temperature, and that the structure is provided with a drain hole similar to that described in the other 50 embodiments.

Where the signaling device is to be used in a vertical position, such as might be the case with a bearing for vertical rolls of a rolling mill the 55 firing spring, such as spring 10 shown in Figure 2, may be dispensed with and gravity may be utilized for shattering the container containing the liquid signaling material. Also, the spring may be dispensed with in those cases where the 60 signaling material is a solid, provided that the 65 signaling device is located in such manner that gravity causes the shearing of the retaining member when the predetermined temperature is reached. The device shown in Figure 10 is essentially similar to that shown in Figure 2, except that no firing spring corresponding to the 70 spring 10 is employed. In the embodiment shown in Figure 10, the striking head 70 is made considerably heavier, so that when the washer 71 of easily fusible material softens upon it reaching a predetermined temperature, the weight of the striking head 70 causes the washer to be sheared by the bolt head 72. Upon release of the striking head 70, it breaks the glass container 73 and the liquid runs out of the drain 75 opening 74. An air vent opening 75 aids in the discharge of the material.

A charge of solid signaling material may be employed instead of a liquid, one such embodiment being illustrated in Figure 11. In this fig- 75

ure, the arrangement of striking head 77, retainer 78, bolt 79, spring 80 and washer 81 of easily fusible material are the same as in Figure 2. The solid signaling material is of a type which liberates a lachrymatory or stench producing gas. If it is desired to produce a lachrymatory gas, a charge 82 of chloracetophenone and smokeless powder may be employed in a foraminous container 83. The container 83 is provided at one end with a detonator 84 and a coating 85 of easily ignitable material is formed on the outside of the foraminous container in order to conduct the combustion over the entire surface area of the mass in the container. The coating 85 may be made of a paste of black powder and a binder such as collodion. The striking head 77 is maintained in spaced relation with respect to the foraminous container 83 by a metallic container 86, and the end of the recess 87 in the bearing block is closed by an end plug 88 provided with openings 89 for the discharge of the gas liberated upon combustion of the charge 82. In operation, the washer 81 of easily fusible material softens when the predetermined temperature is reached, thereby allowing the spring 79 to shear the washer and release the striking head 77. The head strikes against the detonator 84 and ignites the charge 82, the resulting gases escaping through the openings 89.

30 Instead of using signaling material which liberates a smoke or a gas, I may employ an explosive charge which, upon being exploded, causes a noise or report which directs the attention of the operator to the structure to which the signaling device is applied. Thus, in the embodiment shown in Figure 12, I use a blank cartridge 90 containing a charge 91 of powder, the cartridge being provided with a detonator 92 adapted to be operated by a striking head 93 arranged in the same manner as described in connection with Figure 11. The cartridge 90 is received in an end plug 94 which is threaded into the recess 95 in the bearing block 96.

It will be understood that the signaling material may be either liquid, solid or gaseous and of a character to produce a smoke, a lachrymatory or stench gas, or the material may be of an explosive character which, when ignited, explodes producing a report which attracts the attention of the operator of the machine. If a smoke producing liquid is used, I prefer to employ titanium tetrachloride, although a mixture of chlorosulfonic acid and sulfur trioxide may be used. A suitable stench producing liquid is pyridine. For producing lachrymating gases, I may use a solution of chloracetophenone or ethyl bromacetate. A suitable solid mixture for producing smoke contains hexachlorethane, zinc and zinc oxide, to which may be added accelerators such as ammonium perchlorate or potassium nitrate, and a cooling agent such as ammonium chloride. Such mixture produces a smoke upon ignition. The invention is applicable irrespective of the particular type of material for attracting the attention of the operator, and I have therefore designated these various compositions as "signaling material".

70 The invention is applicable not only to protecting parts of rolling mills from overheating, but may be employed in any place where it is desired to attract the attention of an operator if the structure exceeds a certain predetermined temperature. The signaling device may be located adjacent the bearings in all types of machines. It may be used in maintaining at a predetermined

temperature a drying room used for drying powder. It may also be used in connection with hot water boilers, or, in fact, any structure which should be maintained below a predetermined temperature.

I have illustrated and described certain embodiments of my invention. It will be understood, however, that the invention may be otherwise embodied within the scope of the following claims.

I claim:

1. The combination with a structure to be protected against excessive temperature and provided with a recess, of a signaling device located in the recess and adapted to operate at a predetermined temperature, said device comprising a striking head, retaining means for the head including a retaining member of easily fusible material, a firing spring for the head, a frangible container containing a liquid signaling charge, and an end plug in the recess, said structure being provided with a drain opening communicating with the recess, said retaining member adapted to be sheared at a predetermined temperature to release said striking head for breaking said frangible container.

2. The combination with a structure to be protected against excessive temperature and provided with a recess, of a signaling device located in the recess and adapted to operate at a predetermined temperature, said device comprising a striking head, retaining means for the head including a retaining member of easily fusible material, a firing spring for the head, a frangible container containing a liquid signaling charge, means for spacing the retaining means from the frangible container, and an end plug in the recess, said structure being provided with a drain opening communicating with the recess, said retaining member adapted to be sheared at a predetermined temperature to release said striking head for breaking said frangible container.

3. The combination with a structure to be protected against excessive temperature and provided with a recess, of a signaling device located in the recess and adapted to operate at a predetermined temperature, said device comprising a striking head, retaining means for the head including a retaining member of easily fusible material, a firing spring for the head, a frangible container containing a liquid signaling charge, means for spacing the retaining means from the frangible container, and an end plug in the recess, said structure and end plug being provided with a drain opening and an air vent communicating with the recess, said retaining member adapted to be sheared at a predetermined temperature to release said striking head for breaking said frangible container.

4. The combination with a rolling mill provided with a bearing to be protected against excessive temperature, of a signaling device located adjacent the bearing in a recess and adapted to operate at a predetermined temperature, said device comprising a striking head, retaining means for the head including a retaining member of easily fusible material, a firing spring for the head, a frangible container containing a liquid signaling charge, means for spacing the retaining means from the frangible container, and an end plug in the recess, said bearing being provided with a drain opening communicating with the recess, said retaining member adapted to be sheared at a predetermined temperature to release said striking head for breaking said frangible container.

5. A signaling device comprising a striking head, a retaining member of easily fusible material, means extending from the striking head and anchored in the retaining member and arranged to hold the striking head in retracted position and to shear a passage through the retaining member at a predetermined temperature to release said head, and a frangible container containing a liquid signaling material and arranged to be broken by said head.
6. A signaling device comprising a striking head, a sleeve, a retaining member of easily fusible material within said sleeve, means extending from the striking head and anchored in the retaining member and arranged to hold the striking head in retracted position and to shear a passage through the retaining member at a predetermined temperature to release said head, and a frangible container containing a liquid signaling material and arranged to be broken by said head.

7. In combination, a bearing, a housing therefor provided adjacent to said bearing with a bore in communication with the atmosphere, and a telltale comprising a container mounted in said bore, and means mounted in said bore exteriorly of the container therein for rupturing said container at a predetermined temperature of said bearing.

8. In combination, a shaft, a housing therefor, a roller bearing interposed between said shaft and said housing, said housing being provided adjacent to said bearing with a bore having an opening in communication with the atmosphere, and a telltale mounted in said bore comprising a closed vessel adapted to contain a signaling material, and mechanical means for rupturing said container at a predetermined temperature of said bearing to permit the signaling material to escape through said opening.

20

CARL R. WEINERT.
